UNITED STATES PATENT OFFICE.

MONTE C. MERKER, OF READING, PENNSYLVANIA.

BILLBOARD.

Application filed May 20, 1924. Serial No. 714,585.

This invention relates to billboards and particularly to the construction of frame and supports for the same.

The present style of billboard which is almost universally erected has come to be of a standardized size of twenty-five feet length by eleven feet in height. With this great size to support and the present method of support, it has become necessary to build very substantial supports and to place braces at the rear to hold the board rigidly in place. There is great objection to these billboards at the present time due to the fact that the back braces are very unsightly and also to the fact that the back braces become loose and permit the billboards to fall.

The primary object of this invention is to provide an improved billboard frame and supports for the same.

Other objects of this invention are to provide a frame for supporting a billboard which will be (1) adjustably supported at two points substantially mid-distant of each half of its length, (2) adjustable to correct for sagging, at the middle, (3) adjustable to correct for sagging at the ends (4) adjustable to correct for warping at the middle, sides, top and bottom, (5) adjustable forwardly and backwardly (6) firmly held in position without the use of unsightly back braces.

Other and further objects will, from a reading of the specification, be apparent to those skilled in the art.

Referring to the drawing where I have illustrated a preferred embodiment of my invention,

Fig. 1 is an elevation of my invention,

Fig. 2 is a side elevational view,

Fig. 3 is a top plan view,

Fig. 4 is a detail cross sectional view on the line 4—4 of Fig. 1,

Fig. 5 is a detail cross sectional view on the line 5—5 of Fig. 1,

Fig. 6 is a cross section of the lower supporting elements on an enlarged scale,

Fig. 7 is an enlarged cross sectional view on the line 7—7 of Fig. 6,

Fig. 8 is a detail view of the parts for holding the tubular member in place,

Fig. 9 is a detail view on the line 9—9 of Fig. 1,

Fig. 10 is a detail view of the parts adjacent the top of the tubular mast member 20,

Fig. 11 is a cross sectional view on the line 11—11 of Fig. 1,

Fig. 12 is a detail cross sectional view on the line 12—12 of Fig. 1.

The same reference characters refer to the same and similar parts throughout the several views.

The main supporting members of the frame consist of masts 20 which are preferably tubular as indicated by the sectional views. In the herein illustrated embodiment of my invention, I have shown two of these masts. The lower end of each mast 20 slides in a tubular member 21. At the upper end of the tubular member 21 is a means for holding the two tubular members 20 and 21 together. This means, in the embodiment illustrated, comprises a casting 22 having a shoulder 23 between a bored hole, the size of the tubular member 20 and a counter-bored hole larger than the size of the tubular member 21. The two borings are concentric. The two tubular members may have a great variation in size, there being provided a plug 20^a at the bottom of the tubular member 20. This plug 20^a has an outside diameter slightly less than the inside of the diameter of the tubular member 21. At the upper end of the casting 22 is a conical bearing 22^a converging downwardly. The holding means also comprises the complementary semi-cylindrical clamping members 24, each extending almost half way around the tubular member 20 and having an inside diameter equal thereto. Between the tubular members 24 is a sufficient space to allow for tightening. These members 24 are held together by suitable bolts 25 by which they are clamped to the tubular member 20.

At the lower edge of the members 24 are conical faces 26 which are complementary to the conical surface 22^a and operate to wedge and hold the tubular member 20 in any desired adjusted position. At opposite sides of the casting 22 are lugs 27 having holes to receive adjustable brace rods 28.

At the bottom of the tubular member 21 and inside thereof, is a plug 29 which is bolted by a suitable bolt 30 to the inverted channel bar 31. This plug 29 acts to hold the tubular member 21 in fixed relation to the channel bar 31.

Extending across the channel bar, and with their channels upward, are cross chan-

nel bars 32 which are securely fastened to the channel bar 31.

Extending through the outer channel bars 32 and the outer ends of the channel bar 31 are openings through which the hooked ends 33 of the brace bars 28 are passed. It will thus be clear that by adjusting the nuts at the upper ends of the respective brace bars 28, the angularity of 10 the channel bars 31, relative to the tubular members 21, may be changed. As the channel bars 31 support the tubular members 21, 20 and the other parts of the frame and the billboard, it is clear that the billboard 15 will be thrown forward or rearward depending upon the direction of the adjustment of the nuts at the top of the brace rods 28.

In the embodiment described in the drawing, the tubular mast member 20 carries at 20 its top, a member 34 which may be a casting, drop forging or of any suitable construction. This member 34 is in function a strut and retaining member. On its under side is a cylindrical recess in which the tubular mast member 20 is seated as shown in Fig. 9. Adjacent the front and rear of the recess are openings through which pass the rods 35, 36 as shown in Fig. 9. These rods, at their upper ends have nuts threaded 30 thereon as at 37, 38. At the lower ends of these respective rods 35, 36 are connected complementary rods 39, 40. The rods 35 and 39 are held together by the clamp 41 while the rods 36 and 40 are held together 35 by the clamp 42. The lower ends of the rods 39, 40 have respective hooks 43 and 44 which are secured in openings in the channel 31.

By giving initial adjustments by means of 40 the clamps 41, 42, the final adjustments may be made by the nuts 37, 38, thereby giving the tubular mast a tendency to be sprung, one way or the other, depending upon the tension on the nuts 37, 38.

45 The member 34 has lugs through which bolts 45 are passed to secure the same to the frame member 46 which I have found, in practice, convenient to have of a two inch by six inch size and of wood.

50 Adjacent the lugs through which pass the bolts 45, are openings to which are connected the side brace rods 47, 48 as by bolt heads or nuts. The lower ends of the rods 47, 48 are adjustable in a manner to be described.

55 At the outer end of the member 34 is a loop 49 as shown in Fig. 10. This loop 49 has suitable holes for the passage of the brace rods 50, 51, 52 as shown particularly 60 in Fig. 10.

Secured to the tubular mast member 20 adjacent the bottom of the billboard, is a strut member 53 somewhat similar to the member 34, except that the mast passes 65 therethrough and there are no openings for

rods 35, 36, 47 and 48 (see Fig. 6). The outer end of the strut member 53 has a loop shaped portion similar in shape and function to the loop portion 49. The brace rod 35 passes through the opening of the loop shaped portion as shown in Fig. 6. Rods 50, 51 and 52 are connected to the strut members 53 in a manner similar to the connection of the upper rods 50, 51 and 52 to the strut members 34. To the inner side, of 70 the strut members 53, is attached a frame member which I prefer to make of wood and which I have designated 54. This member 54 has a cut away portion in a plane with the axes of the mast and the rod 35. This 75 cut away portion permits the extension of the rod 36 between its points of connection and in a straight line.

Between the wooden frame members 46 and 54 and in the same plane, are two wooden frame members 55, 56 which are attached to each mast by support members 57 shown in Fig. 12. These support members 57 are bolted to the frame members 56 by bolts 58. A set screw 59 is threaded in the outside of 80 the member 57 and impinges in the wall of the mast member 20.

The outer ends of the frame members 55, 56 are connected to attaching member 59 shown in Figures 1 and 11. These attaching members are bolted to the members 55 and 56 and also to the outside frame members 60 at each end.

At the top of the side frame members 60 is secured a top frame member 61 which member is also secured to the wood frame member 46. At the bottom of the side frame members and extending the length of the billboard is the bottom frame member 62. In practice, I have found a convenient size for 105 the frame members 54, 55, 56 to be two inches by four inches, the frame member 46, two inches by six inches and the frame members 60, 61, 62, two inches by eight inches. These frame members 54, 55, 56, 60, 61 and 110 62 are preferably all made of wood. The billboard body 65 is secured to the frame members 46, 54, 55, 56.

At each corner of the frame and securing the frame members 60 to the frame members 46, and 54 are holding members 63, 64. These members are bolted in place and carry lugs to which the rods 50 are secured. The lower members 63 also carry lugs to which are attached the rods 47, 48. Adjustable 115 nuts are placed on the rods 47, 48 and 50 where they pass through and on both sides of the lugs to which they are attached.

Mid-distant between the ends of the frame members 46 and bolted thereto is a securing member 66 shown in Fig. 4. This securing member is hollow at its top. Through the wall of the hollow portion, extends the rod 51. Nuts on both sides of the hollow portions are provided to adjust the nuts in either 125 130

direction and to provide a locking means for any desired adjusted position.

At the bottom of the securing member 66 is a socket in which is held the upright extending member 67. The lower end of this upright member 67 fits into a socket of a member 68 somewhat similar in construction to the member 66. On each side of the member 68 is a lug in which are secured, on respective sides the rods 47, 48. Nuts are threaded on the rods on each side of the lugs to provide for adjustment in either direction and securing the rods when adjusted. The upper ends of these rods as already indicated, are secured by heads or nuts in the openings in the strut members 34.

While the set screws 59 are provided, it is to be understood that they are not intended to carry any great weight and if they are omitted or become loose, the weight will be entirely carried by the members 34, the support for the lower frame portions being provided by the rods 47 and 48.

By adjusting the rods 47, 48 the sagging at the middle and sides can be taken up. When taking up for sagging in the middle, these rods 47, 48 are placed under tension and the upright member 67 assists in raising the upper end of the billboard. The rods 51, 52, 53 at the top and bottom take up for warpage and may be placed in compression or under tension as desired.

The members 31, 32 may be secured to the earth or a building structure or a foundation in any desired manner.

While I have illustrated and described in detail an embodiment of my invention, I desire to have it understood that I do not limit myself to the exact showing and that modifications and changes may be made without departing from the spirit of the invention and within the scope of the appended claims.

Having described my invention, what I claim is:

1. A billboard supporting frame comprising an upright supporting member, means crosswise relative to the upright member and connected thereto and adjusting means connecting opposite sides of the supporting member with the crosswise means at points distant from the supporting member.

2. A billboard supporting frame comprising an upright supporting member, means crosswise relative to the upright member and connected thereto, a plurality of adjusting means connecting opposite sides of the supporting member at different heights, with the crosswise means at points distant from the supporting member.

3. A billboard supporting frame comprising an upright supporting member, means crosswise relative to the upright member and connected thereto, a plurality of pairs of adjusting means connecting opposite sides of the supporting member with the crosswise

means at points distant from the supporting member.

4. A billboard supporting frame comprising an upright supporting member, means crosswise relative to the upright member and connected thereto, a plurality of pairs of adjusting means connecting opposite sides of the supporting member with the crosswise means at points distant from the supporting member, the adjusting means being connected to the supporting means at different heights.

5. A billboard supporting frame comprising an upright tubular supporting means, a telescopic connection to vary the length of the supporting means, a member surrounding the telescopic connection of the supporting means and in contact therewith and a wedge means for holding the telescopic connections in adjusted relation.

6. A billboard frame comprising two upright supporting members spaced from each other, adjusting connections between the supporting members and a point between the same on the frame and an adjusting connection between the two supporting members.

7. A billboard frame comprising two upright supporting members spaced from each other, a plurality of adjusting connections between each of the supporting members and the frame at points between the supporting members at different heights and an adjusting connection between the two supporting members.

8. A billboard frame comprising two upright supporting members spaced from each other, a plurality of adjusting connections between each of the supporting members and the frame at points between the supporting members at different heights, an adjusting connection between the two supporting members and a reinforcing upright member secured adjacent the connected points between the supporting members.

9. A billboard frame comprising a supporting member, a strut member attached to the frame and extending therefrom and at a distance from a side edge thereof, brace members secured to a portion of the strut away from its point of attachment and extending on each side and attached to other portions of the frame.

10. A billboard frame comprising a supporting member, a strut member attached to the frame and extending therefrom and at a distance from a side edge thereof, brace members secured to a portion of the strut away from its point of attachment and extending on each side and attached to other portions of the frame, the brace members being provided with means for placing them under either compression or tension.

11. A billboard frame comprising struts secured in place adjacent the plane of the

billboard and extending outwardly therefrom, brace members attached to the outwardly extending portion of each strut and extending to other portions of the frame and on each side of each strut and means connecting the outer portions of the strut together.

12. A billboard frame comprising struts secured in place adjacent the plane of the billboard and extending outwardly therefrom, brace members attached to the outwardly extending portion of each strut and extending to other portions of the frame and on each side of each strut and means connecting the outer portions of the strut together and means for placing the brace members and connecting means under either tension or compression.

13. A billboard frame comprising a plurality of upright supporting members secured thereto, braces extending from and on opposite sides of the supporting members and connected to portion of the frame lower than the point of attachment of the supporting member and a vertically extending member connecting the lower portions of the frame with the upper portions.

14. A billboard frame comprising a plurality of supporting members secured thereto, braces extending from adjacent supporting members toward each other to a lower point on the frame, a unitary means connecting the braces together and connected to the frame, other braces connected to the supporting members and extending away from each other and connected to lower portions of the frame.

15. A billboard frame comprising a plurality of supporting members secured thereto, braces extending from adjacent supporting members toward each other to a lower point on the frame, a unitary means connecting the braces together and connected to the frame, other braces connected to the supporting members and extending away from each other and connected to lower portions of the frame, and strengthening means connected to the unitary means and extending to and connected to upper portions of the frame.

In testimony whereof I hereunto affix my signature.

MONTE C. MERKER.
